UNITED STATES PATENT OFFICE

116,636

DESIGN FOR A BOOT OR SIMILAR WATER- PROOF ARTICLE

Henry A. Stuart, Providence, R. I., assignor to Goodyear Footwear Corporation, Providence,
R. I., a corporation of Delaware

Application October 31, 1938, Serial No. 80,776

Term of patent 14 years

To all whom it may concern:

Be it known that I, Henry A. Stuart, a citizen of the United States, residing at Providence, in the county of Providence and State of Rhode Island, have invented a new, original, and ornamental Design for a Boot or Similar Waterproof Article, of which the following is a specification, reference being had to the accompanying drawing, forming part thereof.

Figure 2 is a bottom plan view of the same,
showing my new design.

I claim:

The ornamental design for a boot or similar waterproof article, substantially as shown.

HENRY A. STUART.
